(57) **CLAIM**

The ornamental design for an electric bicycle, as shown and described.

DESCRIPTION

FIG. 1 is a front perspective view of an electric bicycle showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a rectangular portion 9 of FIG. 1;

FIG. 10 is an enlarged view of a rectangular portion 10 of FIG. 2;

FIG. 11 is an enlarged view of a rectangular portion 11 of FIG. 2; and,

FIG. 12 is an enlarged view of a rectangular portion 12 of FIG. 5.

The broken lines in the drawings depict portions of the electric bicycle that form no part of the claimed design.
